(57) **CLAIM**

The ornamental design for a mobile phone, as shown and described.

DESCRIPTION

FIG. 1 is a front perspective view of a mobile phone showing our new design according to a first embodiment;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a rear perspective view thereof;

FIG. 9 is a front perspective view of a mobile phone showing our new design according to a second embodiment;

FIG. 10 is a front elevation view thereof;

FIG. 11 is a rear elevation view thereof;

FIG. 12 is a left side elevation view thereof;

FIG. 13 is a right side elevation view thereof;

FIG. 14 is a top plan view thereof;

FIG. 15 is a bottom plan view thereof;

FIG. 16 is a rear perspective view thereof;

FIG. 17 is a front perspective view of a mobile phone showing our new design according to a third embodiment;

FIG. 18 is a front elevation view thereof;

FIG. 19 is a rear elevation view thereof;

FIG. 20 is a left side elevation view thereof;

FIG. 21 is a right side elevation view thereof;

FIG. 22 is a top plan view thereof;

FIG. 23 is a bottom plan view thereof;

FIG. 24 is a rear perspective view thereof;

FIG. 25 is a front perspective view of a mobile phone showing our new design according to a fourth embodiment;

FIG. 26 is a front elevation view thereof;

FIG. 27 is a rear elevation view thereof;

FIG. 28 is a left side elevation view thereof;

FIG. 29 is a right side elevation view thereof;

FIG. 30 is a top plan view thereof;

FIG. 31 is a bottom plan view thereof; and,

FIG. 32 is a rear perspective view thereof.

The dot-dash broken lines in the figures and the evenly spaced broken lines that are immediately adjacent to the shaded areas and define unshaded regions, represent the bounds of the claim. All other broken lines, including the features within broken line boundaries, the broken lines on the front surface to the right and left of the speaker, and the broken lines showing the display, are directed to environment. The broken lines form no part of the claimed design.
